2 SHEETS-SHEET 2.

UNITED STATES PATENT OFFICE.

VICENTE FONT Y AMADOR, OF HABANA, CUBA.

TYPE-WRITER.

1,095,063.

Specification of Letters Patent. Patented Apr. 28, 1914.

Application filed May 13, 1912. Serial No. 697,052.

To all whom it may concern:

Be it known that I, VICENTE FONT Y AMADOR, a citizen of the Republic of Cuba, residing at Vedado, Twenty-third street, Habana, in the Province of Habana and Republic of Cuba, have invented certain new and useful Improvements in Type-Writers, of which the following is a specification.

This invention relates to certain novel and useful improvements in manifold attachments for typewriters.

In carrying out my invention, it is my purpose to provide an attachment or device which may be applied to any of the standard makes of typewriters, and by means of which the process of writing both the original and carbon sheets may be proceeded with continuously and without the necessity of the operator losing time by stopping to change the carbons and paper sheets.

Still a further object of my invention is to provide a simple, compact, convenient and efficient attachment by means of which the desired number of copies may be rapidly made.

With the above recited objects and others of a similar nature in view, my invention consists in the construction, combination and arrangement of parts set forth in and falling within the scope of the appended claims.

In the accompanying drawings like characters of reference indicate like parts in all the views, and Figure 1 is a view in side elevation of an attachment embodying my invention, this view illustrating a machine for making a single carbon copy. Fig. 2 is a front view thereof. Fig. 3 is a diagrammatic view showing a form of machine for making a plurality of carbon copies. Fig. 4 is a detail view of one of the rollers. Fig. 5 is a view of one end thereof. Fig. 6 is a view of the opposite end. Fig. 7 is a view in side elevation of the upper end of one of the standards.

In the present instance, I have shown my attachment as embodying a frame designed to be mounted upon the ordinary typewriter carriage, and carrying a plurality of cylinders or rollers for the continuous sheets of paper and carbon, said sheets running around the ordinary roller or platen of the typewriter.

Referring now to the accompanying drawings in detail, the numeral 1 indicates the ordinary typewriter roller provided with

the shaft 3, the ends of which are supported in the bearings 3' of the carriage A. A plurality of guide rollers 2 are arranged about and extend parallel with the typewriter roller 1. The carriage A is provided with a series of vertical arms or standards 4 preferably arranged in pairs, these pairs of standards or arms supporting the carbon carrying and paper carrying rolls as clearly shown in Figs. 1 and 2.

The numeral 5 designates a cross bar or plate of the carriage, while at 6 and 7, I have shown guide plates extending across the carriage and arranged adjacent to the typewriter roller or platen to direct the paper sheets and carbon sheets thereto, while 8 indicates a hood plate or guide arranged above the platen or roller.

Referring now especially to Figs. 1 and 2, the numeral 9 designates a roller journaled in the rear pair of arms 4 and adapted to receive one end of the continuous carbon sheet or roll C, said carbon running forward and around the typewriter roller 1, and thence up to the second carbon roller 9', journaled in the forward pair of arms 4. The stud shafts 11 and 11' of the rollers 9 and 9' seat in slotted bearings 12 and 12' in the rear and forward pairs of arms, respectively.

The numeral 10' designates a roller for the paper P' similarly journaled in the lower portion of the intermediate pair of arms 4, while the numeral 10 designates a roller for the second roll of paper P journaled likewise in the upper end portion of the intermediate pair of arms 4. The stud shafts for the roller 10 are indicated at 14 and seat in the slotted bearing 15, while the stud shafts for the lower roller 10' are shown at 14' and seat in the slotted bearings 15'. As all of the four rollers, that is to say, the two carbon rollers and the two paper rollers are similar in construction and are provided with like tensioning means for properly

tightening or tensioning the paper and carbon sheets the description of one of the same hereinafter given is applicable to all. The shaft of each roller is provided at one end with a toothed wheel 16 as shown in Fig. 7 against which bears a smaller roller 17 carried at the free end of the pivoted arms 18, while 19 designates a U-shaped leaf-spring connected at 20 to the adjacent arm and normally holding the roller 17 in contact with the toothed wheel by bearing against

the pivoted arm. Each carbon roller is further provided with a longitudinal groove approximately semicircular in cross section and shown at 20' designed to receive a 5 rounded bar 21 pivoted at one end as at 22, the outer surface of the bar lying flush with and forming a continuation of the periphery of the roller. The opposite end of the rod carries a small pin 23 with which engages the bill of the locking hook 24 pivoted at 25 and normally thrown into non-locking position by the U-shaped spring 26.

27 designates a locking lever pivoted at 28 and adapted to bear against and hold the hook in locking position. When placing the carbon paper on the rolls, the lever 27 is depressed so that the hook is thrown out of engagement with the pin by means of the spring thereby enabling the rod to be lifted 20 so that the end of the carbon sheet may be inserted between the rod and the rolls.

The numeral 28' designates a roller bearing against and transmitting motion to the carbon roller 9', said roller 28' in turn receiving motion from the paper roller 10 against which it bears. In order to maintain this roller 28 in proper position and under the necessary tension, I connect to each end of the shaft thereof, one end of a 30 spring 29 the opposite end of each spring carrying a hook 30 for connection with the keeper bolt 31 in the adjacent side of the frame member 4.

From the above description taken in connection with the accompanying drawings the construction and manner of employing my invention will be readily apparent. The original paper sheet and the second paper sheet are positioned as shown in Fig. 1, and 35 after being passed around the typewriter platen with the carbon running therebetween, the ends are allowed to run free in the usual manner. The paper is also further formed of rolls and preferably scored or perforated 40 transversely at proper distances to form the proper length of the sheets. The machine is now operated in the usual manner and as the work progresses, the paper and carbon are drawn off their respective feed rolls, 45 the carbon being rolled on the receiving roll 9' so that when the reel 9 is emptying and the carbon is rolled entirely upon the reel 9', the latter can be substituted or exchanged 50 with the reel 9, and the operation continued 55 as before.

In Fig. 3, I have illustrated diagrammatically a slightly modified arrangement wherein a plurality of second or carbon sheets may be written. In this case in ad-

dition to the carbon reels 9 and 9' and the two paper rolls 10 and 10', I employ an additional pair of paper rolls 10" and 10"". The carbon sheet C running from the roll 9 passes over the guide roller 32 and between the paper from the rolls 10 and 10' around the typewriter platen 3, thence around the guide rolls 33, 34 and 35 to the guide roller 36, thence between the paper rolls 10' and 10" around the typewriter platen again, thence between the tension roller 28' and 60 the guide 33 around the guide rolls 34, 35 and 37, thence between the runs of paper coming from the rolls 10" and 10"" around the typewriter platen once again and up to the carbon roller 9'. From this it will be 65 seen that any suitable number of paper rolls may be employed depending upon the number of copies it is desired to make.

It will be seen that I have provided an exceedingly simple, yet convenient device 70 whereby the writing may be done continuously and without the necessity of the operator stopping to frequently change the carbon sheet and to substitute new paper sheets.

While I have herein shown and described 75 the preferred embodiment of my invention by way of illustration, I wish it to be understood that I do not confine myself to all the precise details of construction herein set forth, as modification and variation may be 80 made without departing from the spirit of the invention, or exceeding the scope of the claim.

What I claim is:

In a typewriter, the combination with a 95 carriage and typewriter platen carried thereby, of guide rollers arranged peripherally about the typewriter platen, front, rear and intermediate standards extending in pairs vertically from the carriage, rolls for carrying the carbon paper mounted on the front and rear standards, a pair of paper carrying rolls mounted on the intermediate standards and arranged one above the other, and a tensioned roller arranged to bear against the 100 uppermost paper roll and the carbon roll carried by the front standard, said tensioned roller transmitting motion from the paper roll to said carbon roll, and guide plates for 105 directing the carbon and the paper to and 110 around the typewriter platen.

In testimony whereof I affix my signature, in the presence of two witnesses.

VICENTE FONT y AMADOR.
